E. MARCUSON

ARTICLE HOLDER

Filed July 24, 1923

INVENTOR
Elias Marcuson,
BY
Fraunfelder and Richards,
ATTORNEYS

UNITED STATES PATENT OFFICE.

ELIAS MARCUSON, OF NEW YORK, N. Y.

ARTICLE HOLDER.

Application filed July 24, 1923. Serial No. 653,420.

To all whom it may concern:

Be it known that I, ELIAS MARCUSON, a subject of the King of Great Britain, residing at New York, in the county of New 5 York and State of New York, have invented certain new and useful Improvements in Article Holders; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification. 15

This invention relates, generally, to a novel implement or attachment for use with type-writing machines adapted to receive and serve as a holder for the usual 20 perforate eraser-plate, for rubber erasers of the various shapes used by typists, and for the support of a lead-pencil, pen, or the like.

With the above in view, the invention has for its principal objects to provide a neat 25 and simply-constructed holder for supporting within easy reach of the typist, such articles as above mentioned, and, furthermore to provide an implement or device which is adapted to be readily attached in 30 a convenient position with relation of the main frame of a type-writing machine.

Other objects of this invention not at this 35 time more particularly enumerated, will be fully understood from the following detailed description of the present invention.

The invention consists, primarily, in the novel implement or attachment for type-writing machines hereinafter more fully set forth, and in the details of the construction 40 of the various parts thereof, all of which will be more fully described in the following specification, and then finally embodied in the clauses of the claim which are appended to and which form an essential part of the 45 said specification.

The invention is clearly illustrated in the accompanying drawings, in which:—

Figure 1 is a perspective view of a fragmentary portion of a type-writing machine, 50 and also of a holder attached to the frame of the machine, said view illustrating more particularly a pencil and eraser-holder or support made according to and embodying the principles of the present invention.

Figures 2 and 3 are elevations or face views of the obverse and reverse sides of the

holder or support; Figure 4 is an edge view of the same; and Figure 5 is a horizontal sectional representation, taken on line 5—5 in Figure 2, looking in the direction of 60 the arrow *x*.

Similar characters of reference are employed in the said above described views, to indicate corresponding parts.

Referring now to the several figures of 65 the drawings, the reference-character 1 indicates one of the standards or foot-pieces of a type-writing machine, provided at its lower end-portion with the usual rubber cushion 2.

The pencil and eraser-support or holder which is adapted to be used with the said post and rubber cushion, substantially in the manner illustrated in Figure 1 of the drawings, comprises a base-plate 4 and an 75 article-supporting plate 5 extending vertically in an upward direction from said base-plate, and preferably along one of the marginal end edges of said plate. Forced outwardly and rearwardly from said supporting plate 5, at or near the angle formed by the base-plate 4 and the said supporting plate 5, is a resilient clamping tongue, as 6, which is preferably bent, as at 7, so as to provide suitable means to permit withdrawal from and slipping into retaining position between the curved holding portion 8 of the tongue 6 and the rear face 9 of the plate 5 of the usual perforate erasing plate 10, as will be clearly understood from an 90 inspection of Figures 1 and 4 of the drawings. The said supporting plate 5 is also provided along its marginal side edge-portions 11, or in any other suitable part of the plate, with means, preferably in the form of 95 angular or hook-shaped lugs, as 12, which, as will be evident, serve as supports for holding a pencil 13, or the like in a position readily at hand for use by the typist. At or near its upper end-portion, the said supporting plate 5 is made with oppositely extending angularly shaped edge-portions or wings 14 and 15 usually and preferably of triangular configuration, said portions or wings 14 and 15 being integrally connected 105 with the plate 5. Integrally connected with and projecting forwardly from the lower oblique edge of each portion or wing 14 and 15 is a supporting member or flange 16, each flange 16 being provided with a marginal 110 and upwardly extending clamping element 17. These elements 17 are usually of simi-

lar configuration to those of the edge-portions 14 and 15, and are suitably inwardly curved or bent, as at 18, so as to provide the device with resilient clamping ears or 5 lugs for suitably maintaining the various shapes of erasers 19, 20 and 21, in removably clamped or held positions, for use by the typist, substantially as illustrated in Figures 1, 2 and 3 of the drawings. In order 10 to provide a proper clamping relation of the parts just described with the long rectangular erasers such as 19, when the latter is engaged between the opposed inner vertical margins of the clamping elements 17, as shown in Fig. 1, the main portion of the supporting plate 5 is preferably longitudinally slitted, as at 22, to provide resiliency, and hence greater clamping action; and, that the erasers and especially 15 circular erasers such as 21, may be more readily grasped by the typist for withdrawal from the pencil and eraser-holder or support, the portions or wings 14 and 15 are preferably marginally cut away, as at 20 23, and as more particularly shown in Figure 2 of the drawings.

To secure the device in its operative position, in a convenient location, the base-plate 4 is preferably placed between the 30 upper surface of the table or type-writer desk 3 and the rubber cushion 2, the weight of the type-writing machine suitably and properly maintaining the holder or support alongside of the frame or post 1 of the type-writing machine as clearly indicated in Figure 1 of the drawings.

If desired, and as an extra precaution, the base-plate 4 of the holder or support may be formed with suitably disposed and upwardly projecting and pointed imbedding prongs, as 24, which may be readily forced into the lower portion of the rubber cushion 2, and thereby serves as a retaining means for holding the pencil and eraser-support or holder in its upright position against accidental displacement, as will be clearly evident. If desired, the base-plate 4 may be arranged between the cushion 2 and the foot-piece of the machine frame, so that the 45 shank of the cushion 2 passes through the slot 25 of said base-plate.

In practice, I prefer to make the pencil and eraser-support or holder from metal, usually aluminum, but this is not essential, 50 since the device may be made of any suitable metal; or, if desired it may be made of any other suitable material, such as celluloid, hard rubber, or the like.

I am also aware, that the general arrangement and construction of the parts of the device may be changed without departing from the scope of the present invention as set forth in the foregoing specification, and as defined in the clauses of the claims which 55 are appended thereto. Hence, I do not limit

my present invention to the exact arrangements and construction of the parts as described in said specification, and as illustrated in the accompanying drawings.

I claim:—

1. An accessory support for typewriting machines in the form of a unitary device, comprising a base-plate for engagement beneath the foot-piece of a typewriting machine, an upstanding supporting plate integrally connected with the outer end of said base-plate, and a plurality of retaining elements integrally connected with said supporting plate for removably supporting various accessories, certain of said retaining elements cooperating with the rear face of said supporting plate, while the remaining retaining elements cooperate with the front face of said supporting plate.

2. In an accessory support for typewriting machines, a base-plate for engagement beneath the foot-piece of a typewriting machine, an upstanding supporting plate integrally connected with the outer end of said base-plate so as to be disposed in a plane parallel to the side of the typewriting machine, and an eraser supporting means connected with the upper free end portion of said supporting plate, comprising a pair of oppositely and laterally extending triangular wings projecting from said supporting plate, outwardly and forwardly projecting supporting flanges springing from the lower oblique margins of said wings, and inwardly projecting retaining elements springing from the free outer margins of said supporting flanges so as to lie in a plane substantially parallel to and forwardly offset from said wings.

3. In an accessory support for typewriting machines, a base-plate for engagement beneath the foot-piece of a typewriting machine, an upstanding supporting plate integrally connected with the outer end of said base-plate so as to be disposed in a plane parallel to the side of the typewriting machine, and an eraser supporting means connected with the upper free end portion of said supporting plate, comprising a pair of oppositely and laterally extending triangular wings projecting from said supporting plate, outwardly and forwardly projecting supporting flanges springing from the lower oblique margins of said wings, inwardly projecting retaining elements springing from the free outer margins of said supporting flanges so as to lie in a plane substantially parallel to and forwardly offset from said wings, said retaining elements having opposed vertical inner margins spaced laterally apart, and said supporting plate intermediate said wings having a downwardly extending slit for the purposes described.

4. In an accessory support for typewrit-

ing machines, a base-plate for engagement beneath the foot-piece of a typewriting machine, an upstanding supporting plate integrally connected with the outer end of 5 said base-plate so as to be disposed in a plane parallel to the side of the typewriting machine, and an eraser supporting means connected with the upper free end portion of said supporting plate, comprising a pair 10 of oppositely and laterally extending triangular wings, projecting from said supporting plate, outwardly and forwardly projecting supporting flanges springing from the lower oblique margins of said wings, in- 15 wardly projecting retaining elements springing from the free outer margins of said supporting flanges so as to lie in a plane substantially parallel to and forwardly offset from said wings, and the upper extremity of said supporting plate intermediate said wings having an indented portion for the purposes described.

5. In an accessory support for typewriting machines, a base-plate for engagement beneath the foot-piece of a typewriting machine, an upstanding supporting plate integrally connected with the outer end of 25 said base-plate so as to be disposed in a plane parallel to the side of the typewriting machine, and a pencil or pen supporting 30

means integrally connected with said supporting plate, comprising a pair of forwardly projected lugs having upturned free ends outwardly offset from the outer face of said supporting plate, and said lugs being respectively struck up from the respective marginal side portions of said supporting plate. 35

6. In an accessory support for typewriting machines, a base-plate for engagement 40 beneath the foot-piece of a typewriting machine, an upstanding supporting plate integrally connected with the outer end of said base-plate so as to be disposed in a plane parallel to the side of the typewriting machine, and an eraser plate holding means integrally connected with said supporting plate, comprising an upwardly directed spring tongue struck out of the lower end portion of said supporting plate and being rearwardly bent to cooperate with the rear face of the latter. 45 50

In testimony, that I claim the invention set forth above I have hereunto set my hand this 20th day of July, 1923.

ELIAS MARCUSON.
